UNITED STATES PATENT OFFICE.

PATRICK LEE HUGGINS, OF DECATUR, GEORGIA.

CLEAT.

Application filed January 5, 1925. Serial No. 682.

To all whom it may concern:

Be it known that I, PATRICK LEE HUGGINS, a citizen of the United States, residing at Decatur, in the county of De Kalb and State of Georgia, have invented certain new and useful Improvements in Cleats; and I do hereby declare the following to be a full, clear, and exact description of the invention, such as will enable others skilled in the art 10 to which it appertains to make and use the same.

The present invention relates to improvements in cleats and has particular reference to a cleat for use in connection with a rail-way car door.

An object of the invention is to provide a device which will discourage and prevent theft from railway freight cars and to this end I propose an improved cleat for securing the car door closed which will be inaccessible either from the ground or from the roof of the car except when the car is standing at a loading or discharging platform, whereupon an authorized person standing 25 on the platform will have easy access to the same.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 shows a fragmentary side view of a railway car with the improved devise thereon.

Figure 2 is an enlarged view showing parts of the door and car body with the device applied thereto and partly shown in section.

Figure 3 is a view taken at right angles to Figure 2 and showing the car body in section with the device in locked position.

Figure 4 is a cross section taken through parts of the door and car body through the improved device with the latch member moved out of locked position, and

Figure 5 is a section taken on line 5—5 in Figure 2.

Referring more particularly to the drawings 6 indicates the side of a car or the car body and 7 the usual horizontal sliding door found on standard freight cars.

In accordance with the present invention the car door along one edge is provided with

a recess 8 for the reception of the casing 9 containing the pivoted latch member 10. This latch member extends substantially vertically in the casing and is adapted to rock upon the pivot bolt 11 extending substantially through the central part thereof. The pivot bolts extend through the casing and is provided with the washer and nut 12 to hold the coil spring 13 in place upon the bolt and upon the exterior of the bottom portion of the casing. This spring holds the latch member 10 frictionally against the interior of the bottom wall of the casing and tends to resist the swinging movement thereof except when positively pushed by hand. The bottom of the casing is held away from the bottom of the recess 8 by the use of the sleeves 14 which extend about the fastening members 15. These fastening members have 75 heads countersunk in the bottom of the casing and pass through the spacing sleeves and into the car door.

The spacing sleeves surround the fastening members between the bottom of the recess 8 and the bottom of the casing 9. In this way the casing is held away from the bottom of the recess to leave ample room for the projecting pivot bolt 11.

The casing 9 is a narrow one elongated 85 in a vertical direction and the latch member 10 is substantially wide so as to permit of only a small rocking movement in the narrow casing. The upper end of the latch member is preferably large and wide 90 so as to act as a stop in striking the casing wall when in the position shown in Figure 4 to avoid too great a movement in the unlatching direction. The upper part of the latch member is narrower and extends 95 through the slot 16 in the lower wall of the casing. A laterally enlarged lug 17 is made upon the lower projecting end of the latch member and plays back and forth in the lower part of the recess 8 below the casing. 100 This lug 17 provides a convenient grasp by which to rock the member 10 back and forth and it is provided with a hole 18 to register with the hole 19 when the member 10 is in the locked position. Through these holes is adapted to be passed the cord 20, the ends of which are secured in the seal 21. The latch member 10 is provided with the extension nose 22 projecting toward the car body and provided with the under cut 110 notch 23 for engaging about the stirrup or yoke 24. This latter yoke is affixed in the

recess 25 of the car body so that the cross piece of the yoke, with which the slotted nose 22 engages, extends out from the base of the recess 25 and freely to be engaged by 5 the nose. Nuts or other fastenings 26 are employed to hold the yoke piece in place. At 27 is shown a slot in the side wall of the casing to permit the nose 22 to play in and out.

10 The casing is closed normally by the swinging cover plate 28 suspended from the bolt 29 passing through the upper part thereof and through a perforated boss 30 upstanding from the casing. The nut and 15 washer 31 upon the inner end of the bolt 29 is used to hold the coil spring 32 in place.

This coil spring exerts a tension on the cover plate and tends to hold it frictionally wherever placed. The cover plate is provided with lugs 33 adapted to enter depressions in the upper edge of the casing when the cover plate is in closed position. These lugs will move out of the recesses by the application of slight force and the cover plate 25 may move outwardly compressing the spring 32.

In the use of the device, the latch member 10 is swung into the position shown in Figure 3 where the nose 22 engages with the stirrup and locks the car door 7 in the closed position shown in Figure 1. The seal is put in place and the cover plate closed.

This operation takes place after loading by an authorized employee. The device is placed near the upper edge of the door and is nine feet from the ground and about four or five feet from the top of the car so that it is inaccessible to thieves standing upon the ground or reaching down from the top 40 of the car. It is also sunk flush in with the edge of the car door and for this reason it is difficult to get at unless using a ladder whereupon the thief immediately becomes conspicuous.

45 However, the device is easily accessible from a platform. The seal is broken by one authorized so to do when the car reaches its destination, the latch member is thrown back to the position shown in Figure 4 and the door 7 may be opened.

It is obvious that various changes and modifications may be made in the details of construction and design of the above specifically described embodiment of this invention without departing from the spirit 55 thereof, such changes and modifications being restricted only by the scope of the following claims.

What is claimed is:—

1. In combination with a freight car having a sliding door with a recess therein, a casing carried in said recess spaced from the bottom of the recess, a pivoted latch member in the casing, spring means behind the casing for pressing the latch member 60 against the casing, means whereby said latch member may be sealed in latched position, a cover plate for said casing and recess, and means carried by the car body for cooperating with the latch member to hold 65 the door in closed position.

2. In combination with a railway freight car having a sliding door with a recess therein near its upper edge, a casing fitted in said recess, means to hold the casing away 70 from the bottom of the recess, a latch member in said casing, a bolt passing through the casing and latch member, spring means for drawing said bolt and latch member against the casing, means for sealing said 75 latch member, a notched nose on said latch member adapted to project beyond the casing and door, and means on the car body for receiving said notched nose.

3. In combination with a railway freight 80 car having a sliding door with a recess thereon, a casing in the recess means for holding the casing away from the bottom of the recess, the lower wall of said casing 85 having a slot therein, a latch member pivoted in said casing with its lower end extending through said slot, a lateral lug on said extending end having a perforation, said casing having a perforation to align 90 with the first named perforation, a sealing member adapted to pass through said perforations, and means on the car body for cooperating with the latch member.

PATRICK LEE HUGDINS.
